Patented July 7, 1914.

UNITED STATES PATENT OFFICE.

ALEXANDRE VALÈRE NIBOUREL, OF PARIS, FRANCE, ASSIGNOR TO UNDERWOOD TYPEWRITER COMPANY, OF NEW YORK, N. Y., A CORPORATION OF DELAWARE.

TYPE-WRITING MACHINE.

1,102,429.

Specification of Letters Patent.

Patented July 7, 1914.

Application filed June 25, 1913. Serial No. 775,640.

To all whom it may concern:

Be it known that I, ALEXANDRE VALÈRE NIBOUREL, a citizen of France, residing in the city of Paris, Department of Seine, France, have invented certain new and useful Improvements in Type-Writing Machines, of which the following is a specification.

This invention relates to key-set tabulators for typewriting machines, and particularly to means for restoring the column stops to normal positions. This return of the operative stops has been effected by setting a cam into the path of the stops, and then running the typewriter carriage back and forth until all stops were cammed to their inoperative positions. This returning cam was oftentimes displaced by the stops, which were jammed against the side 20 of the rack teeth. I aim to devise means for overcoming the binding of the stops when being returned; and also to produce a greater efficiency and accuracy with less power for the operation of the resetting 25 means, by causing the latter to work in the same direction as the movement of the column stop.

A further feature is the return of all stops simultaneously by the mere depression of a key, saving time and labor required to run the carriage back and forth.

Other features and advantages will hereinafter appear.

In the accompanying drawings, Figure 1 is a perspective view showing part of the usual Underwood machine, and a method of how my invention may be applied to said machine. Fig. 2 is a detail view showing a tabulator stop moved into an inoperative 40 position. Fig. 3 is a view showing the tabulator stop returning device in its normal position, and one of the tabulator stops moved into its operative position.

The carriage 1 is usually skipped a number of letter spaces by depressing one of a series of decimal tabulating keys 2, to raise a counter stop 3 into the path of a stop 4 set in rack 5, which is fixed on the carriage, the latter being released from the letter-space 50 escapement (not shown) simultaneously with the raising of the counter stop 3. A stop 4 is placed on the rack at every letter-space interval. These stops, however, are normally withdrawn to ineffective positions, 55 Fig. 2.

When the operator desires to set a stop for a certain column; the carriage is first adjusted to the desired printing point, whereupon the stop-setting key 6 is depressed to draw down the link 7 and rock the shaft 8, 60 which transmits its motion by means of the crank arms 9, 10 and link 11, to the shaft 12, to swing the finger 13 against a stop 4, to push the latter forwardly into its effective position shown in Fig. 3. The finger 13 is 65 positioned at the rear of the machine, to engage whichever stop registers with the printing point, and is returned to a normal position by springs 14.

When the positions of the columns are to 70 be changed, the previously set stops must be rendered ineffective, and then new stops must be set. To accomplish the returning of the stops 4, a rock shaft 15, provided with a plate 16, is mounted preferably above and 75 to the front of the stops, so that when lever 17 (attached to said rock shaft 15) is depressed, the plate 16 will force back any stop which has been set forward. The stops 4 are cut-away at their forward ends 18, so 80 as to freely pass over the counter stops 3, when the column stops are in their ineffective positions. To guard the stops 4 against accidental dislodgment a spring-pressed bail 19 which comprises a detent bar 85 common to all the stops, seats itself in notches 20 when the stops are in either effective or ineffective positions.

Variations may be resorted to within the scope of the invention, and portions of the 90 improvements may be used without others.

Having thus described my invention, I claim:

1. In a typewriting machine, the combination of a tabulating device for positioning 95 the carriage along the writing line, said device comprising a rack and stops slidably embracing said rack, said stops being operative in a direction perpendicular to their line of movement, key-set means for moving 100 said stops selectively from an inoperative to an operative position, and a detent bar common to all of said stops to hold them in the positions to which moved.

2. In a typewriting machine, the combination of a tabulating device for positioning 105 the carriage along the writing line, said device comprising a rack and stops slidably embracing said rack, said stops being operative in a direction perpendicular to their 110

line of movement, key-set means for moving said stops selectively from an inoperative to an operative position, key-controlled means to engage the front of said stops to return them to their inoperative positions, and a 5 detent bar common to all of said stops to hold them in both their operative and inoperative positions.

3. In a typewriting machine, the combination of a tabulating device for positioning the carriage along the writing line, said device comprising a rack and stops slidably embracing said rack, said stops having notches and being operative in a direction 10 perpendicular to their line of movement, key-set means for moving said stops selectively from an inoperative to an operative position, and a spring-pressed bar common 15 to all said stops to engage in said notches

and hold said stops in the positions to which 20 moved.

4. In a typewriting machine, the combination of a tabulating device for positioning the carriage along the writing line, said device comprising a rack and stops slidably 25 embracing said rack, said stops having notches and being operative in a direction perpendicular to their line of movement, key-set means for moving said stops selectively from an inoperative to an operative 30 position, and a key-controlled rock shaft having a plate to return said stops from an operative to an inoperative position.

ALEXANDRE VALÈRE NIBOUREL.
